HOLDER FOR PLAYING CARDS OR THE LIKE

Morris Saltzman, New York, N. Y.

Application January 14, 1952, Serial No. 18,054

Term of patent 14 years

(Cl. D34—13)

To all whom it may concern:

Be it known that I, Morris Saltzman, a citizen of the United States of America, residing in New York city, county of New York, and State of New York, have invented a new, original, and ornamental Design for a Holder for Playing Cards or the like, of which the following is a specification, reference being had to the accompanying drawing, forming part thereof, wherein,

The rear of the holder for playing cards or the like is substantially the same in appearance as the front shown in Figure 1.

I claim:

The ornamental design for a holder for playing cards or the like, substantially as shown and described.

MORRIS SALTZMAN.
